OF D 12,551

DESIGN FOR A SCREEN FOR COILS OF HOT-WATER AND STEAM PIPES.

Design No. 12,551, dated November 1, 1881.

UNITED STATES PATENT OFFICE.

HENRY W. GARTH, OF MONTREAL, QUEBEC, CANADA, ASSIGNOR TO
CHARLES GARTH & CO., OF SAME PLACE.

DESIGN FOR A SCREEN FOR COILS OF HOT-WATER AND STEAM PIPES.

SPECIFICATION forming part of Design No. 12,551, dated November 1, 1881.

Application filed September 3, 1881. Term of patent 7 years.

To all whom it may concern:

Be it known that I, HENRY W. GARTH, a subject of the Queen of Great Britain, residing at the city of Montreal, in the district of 5 Montreal and Province of Quebec, in the Dominion of Canada, have produced a certain new and original Design for Screens for Coils of Hot-Water and Steam Pipes, of which the following is a specification, reference being had 10 to the accompanying drawings, forming part thereof.

The said screen for hot-water and steam pipes may be described as made up of panels upon which are seen birds of different kinds 15 dispersed or displayed among water-lilies and other foliage, ornamental ringed bands or arches also passing across the panels between division-posts and about midway between a molded cornice which runs around the upper 20 edge of the screen and a base molded in a somewhat similar manner. Figured posts or pilasters will also be used at the corners of the screen, and ornamental returns after a corresponding design to the panels will be displayed at each end. 25

Figure 1 is a perspective view of my newly-designed screen, showing three panels and one pilaster; and Fig. 2, a view of returned end, these two views being deemed necessary 30 to fully illustrate my design.

The panel A has on its lower part the figure of a lyre-bird, (*Menura superba lyra*), arranged with its upwardly-projecting tail in the center of the panel, it being also shown as chasing 35 a butterfly which has lodged among foliage at one side of the panel. Leaves of tropical plants are also shown underneath the bird's feet, and foliage extends upward on both sides. Above the lyre-shaped tail there is shown an 40 arched band made up of rings placed between two straps, and on the upper or other side of this band is more foliage, in which are two love-birds, a semicircular ornament being also shown immediately under the molded cornice.

45 The next panel, or that marked B, is somewhat similar to A in its foliage and general arrangement, but two cranes (*Gruidæ*) occupy

the lower half of the panel, one being represented as holding a worm in its bill and the other with its bill touching its back. 50

C represents the third panel of a design corresponding with the others, only in its lower part is shown a love-bird with wings extended among foliage of tropical plants, and above the central arched band a crested parrot and 55 two paroquets are represented perched among the foliage.

The above-described panels are divided by double upright bars with enlarged central spaces, between which run vines and foliage. 60

D is the corner-post or pilaster ornamented with leaves and figures, and provided with molded cap and base, and E shows the return, which is of a design to match the panels A B C. 65

I wish it to be understood that I do not limit myself to the use of all the ornamental panels herein shown in combination, as in cases where the screen is of greater or less size one or more of these panels may be used, as required. 70

What I claim, and desire to secure by Letters Patent, is—

1. The design for a screen herein shown and described, the same consisting of the panels A B C, post or pilaster D, and return E, all 75 combined.

2. In a screen for hot-water or steam pipes, the panel A, consisting of the representation of a lyre-bird, two love-birds, and foliage, arranged substantially as shown and described. 80

3. In a screen for hot-water or steam pipes, the panel B, consisting of the representation of two cranes, two love-birds, and foliage, arranged substantially as shown and described.

4. In a screen for hot-water or steam pipes, 85 the panel C, consisting of the representation of a love-bird, a crested parrot, and two paroquets, arranged with foliage, substantially as shown and described.

HENRY W. GARTH.
